UNITED STATES PATENT OFFICE.

WILLIAM FELS, OF ELBERTA, ALABAMA, ASSIGNOR TO MAX NYDEGGER, OF ELIZABETH, NEW JERSEY.

CAM-CONTROL MECHANISM FOR KNITTING MACHINES.

Original application filed July 8, 1920, Serial No. 394,678. Divided and this application filed September 3, 1921, Serial No. 493,311. Renewed July 21, 1925.

To all whom it may concern:

Be it known that I, WILLIAM FELS, a citizen of Austria, residing in Elberta, county of Baldwin, and State of Alabama, have invented an Improvement in Cam-Control Mechanism for Knitting Machines, of which the following is a specification.

The present invention relates to an improvement in knitting machines, and more particularly to the lock change mechanism thereof. One object has been to provide a machine which shall be fully or partly automatic and at the same time of relatively simple construction with a minimum of mechanically controlled and actuated parts. A further object has been to provide relatively simple means for preventing injury to the machine in case of careless or erroneous operation.

It is known that knitting machines, automatic in varying degrees, have been devised but these machines are usually of complicated design and involve a multiplicity of mechanical movements which not only make the machine expensive to manufacture, but also cause frequent breakdowns and make it necessary for the operator to devote considerable attention to repairs and adjustments.

According to the present invention, I utilize substantially the well known framework and opposed front and rear needle beds of a flat links links machine, although I do not intend to limit the application of the present invention to machines of this type, it being contemplated that the same or similar principles of operation may be applied to other types of knitting machines with suitable modifications. In connection with

the flat double bed machine, I use a reciprocating carriage preferably automatically reversible in direction and which carries with it suitable means for effecting various pattern and thread changes in the knitted fabric. A complete operative knitting machine will preferably include besides the lock change or cam positioning means for controlling the action of the needle jacks to produce either flat or links links operation according to a predetermined order, means

for varying the stitch length according to a predetermined arrangement, and means for changing the thread or yarn, although the device forming the subject matter of the present application will perform its functions independently of the operation of the stitch length and thread changes.

Co-operating more particularly with the lock change or the links to flat change portion of the mechanism arranged on the carriage, is a jack engaging device for automatically selecting jacks or combinations of jacks and moving them into and out of operative position. This device may conveniently be referred to as a jacquard and is intended to perform automatically, and without stopping the machine, substantially the same functions which are now commonly performed only by hand in the case of knitted fabrics of complicated design.

Further elasticity in the operation of the machine and in the character of the fabric produced is permitted by the provision of racking mechanism arranged to operate only in conjunction with or subsequent to a predetermined arrangement of the jacks and needles, said arrangement and said racking being effected automatically and without stopping the machine.

It is contemplated that the lock change may be controlled automatically with other pattern changes if desired, and by electrical means through the instrumentality of a suitable pattern chart having perforations arranged in the path of contacts, said contacts forming part of electrical circuits connected with and controlling the operation of corresponding change mechanisms of the machine. Thus, the chart may be rotated around the periphery of a drum in such a way that perforations will occur in predetermined relative positions in the path of the contacts and at the proper time to effect corresponding changes in the operation of the machine and thus in the pattern of the fabric. The claims of the present application will, however, be limited to the invention embodied in the lock change mechanism as described and disclosed in my co-pending application, Serial No. 394,678.

filed July 8, 1920, of which the present application is a division.

One embodiment of my invention is illustrated in the drawings accompanying the 5 present specification, and in which

Figure 24, a side elevation thereof partly in section.

Referring to the drawings, a machine embodying my invention may conveniently

50 comprise a framework A supporting a fixed rear needle bed B and a front needle bed C preferably slidable both longitudinally and laterally (Figure 3). A reciprocating carriage D is arranged above the needle beds B and C, said carriage being driven by any suitable means such as a motor E operatively connected to a drive chain 101, said chain having a slotted member 102 adapted to receive and engage the free end

55 of a lever pivotally mounted on the carriage at 104 (Figures 3 and 18). As shown more clearly in Figures 1 and 2, the chain 101 is mounted on sprockets arranged at opposite ends of the machine, said 60 sprockets being driven by a belt or other

connection with the motor E. To effect the reciprocating motion of the carriage, means are provided for periodically reversing the direction of the current through the armature of the motor thus reversing the direction of the chain 101. To accomplish this reversing operation automatically, a reversing switch is interposed in the power circuit, said switch being controlled by a double relay indicated at F in Figure 7 of 70 the drawings, the opposed magnets of which are alternately energized at the end of each run of the carriage, the circuit being closed through suitable contacts mounted on the framework of the machine and on the carriage respectively. However, before reversing the current in the armature of the motor, it is desirable to reduce the current or otherwise impede the movement of the carriage so as to avoid harmful impact thereof at the ends of its course. As shown in Figure 7, the motor circuit includes the conductors 105 and 106, the latter of which contains a resistance 107 and also a parallel resistance or manually operable rheostat 108. To increase the resistance in the conductor 106, the rheostat 108 may also be periodically cut out. This is conveniently accomplished by means of a relay including a magnet 109, said magnet being in circuit with both magnets of the double relay F and also with the fixed contact R at one end of the machine, an adjustable contact R' at the opposite end of the machine, and a movable circuit closing contact R'' mounted on the carriage D. For practical purposes, the magnet 109 and the double relay may operate substantially simultaneously. However, the action of the double relay may be effectively delayed by making the bar 110 thereof heavier than the bar 111. Thus, the current in the motor E will be reduced either simultaneously with or just before the change of direction of the current therein. Obviously, although I have described an automatically reciprocating drive for the carriage, any other suitable means for oscillating the carriage may be employed.

110 In addition to the automatic features associated with the reversing mechanism, I have also provided automatic means for controlling and actuating in predetermined succession those parts of the device which operate more particularly to form the fabric and to govern the character of the pattern thereof. This automatic control is effected through a combination of electrical and mechanical arrangements which are measurably simpler than those commonly utilized for a similar purpose in the knitting art and, at the same time effect a highly desirable uniformity and certainty of operation. The control apparatus, according to my invention, co-operates with the driving mechan- 115 120 125 130 135

nism in such a manner that the necessary changes of certain parts are effected at the proper time to secure the desired design of fabric and also to prevent injury to the machine, the latter result being accomplished through the instrumentality of suitable safety devices. The general scheme of control includes a system of circuits each having one set of contacts which engage according to a predetermined arrangement, so that no change is effected unless both sets of contacts are in engagement simultaneously. Referring to Figures 3 and 7 of the drawings, the periodically operating contacts are represented at H, J and K, the contacts H being fixed at one end of the machine, the contacts J being slidably mounted at the other end of the machine, so that the length of stroke of the carriage may be varied, and the contacts K being mounted on the carriage to reciprocate therewith. Thus, some of the contacts K engage all of the contacts H at each stroke toward the left end of the machine, while some of the contacts K engage all of the contacts J at each stroke toward the right end of the machine. All of the contacts H and J are in circuit with a rotating drum 201, the details of which are more clearly disclosed in Figures 9 to 11 inclusive. Intermittent movement is imparted to the drum 201 by suitable means connected with the reciprocating carriage and operated thereby. Thus, the carriage is provided with an upwardly projecting cam shaped member 202 (Figure 3) which moves in the path of a lever 203 (Figure 6) and deflects one end of said lever upwardly. The lever 203 is securely fastened to a rod 204 (Figure 3) journaled in the framework of the machine and having a lever arm 205 secured at one end. A link 206 pivoted at 207 imparts a rocking motion to a pawl carrier 208 pivotally mounted at 209 (Figure 11). A spring pressed pawl 210 engages a ratchet 211 which is operatively connected to the drum 201 and imparts intermittent movement to said drum to the extent of one step during each stroke of the carriage. A contact carrier 212 is mounted adjacent to the drum 201 and is provided with a plurality of perforations adapted to accommodate plunger contacts 213 normally pressed toward the drum by means of springs 214. The carrier 212 is pivotally mounted at 215 and is connected to the pawl carrier 208 by means of a link 216. A spring 217 may be provided to hold the contact carrier normally in position to permit the plunger contacts 213 to engage the peripheral surface of the drum 201 or, when in operation, the surface of a pattern chart 218 arranged to cover the surface of said drum. A yielding detent 219 engages the ratchet 211 to prevent lost motion. As indicated in Figure 10, the pattern chart 218 is provided with perfora-

tions 220 which receive corresponding sprocket projections 221 extending from the peripheral surface of the drum 201. The surface of the chart may be provided with transverse and longitudinal markings 231 and 232, respectively, by which the pattern controlling perforations 222 and 223 may be more readily located and identified as to function.

In the embodiment of my invention illustrated in the drawings, the pattern chart will move twice between each two of the perforations 220. In other words, the pattern chart will travel a distance equal to the distance between two perforations 220 during a complete oscillation of the carriage D; but the movement will take place in two increments. Thus, a change perforation 222 occurring on the same transverse line with the perforations 220 will indicate a change to be effected at the end of a run of the carriage in one direction while a change perforation 223 indicates a change to be effected at the end of a run of the carriage in the opposite direction.

In operation, the plunger contacts 213 bear yieldingly against the surface of the pattern chart 218 and, as the perforations 222 and 223 come into register with said plunger contacts, the latter are permitted to extend through said perforations, thus, in each case, closing a circuit. This operation takes place intermediate the ends of the carriage runs so that, when the carriage reaches one end or the other of its course, one or more changes will take effect, depending upon the number of perforations through which the plungers 213 are properly projecting into contact with the drum 201.

It is contemplated that the points in the formation of the fabric at which lock changes are to occur will be indicated on the control chart by means of suitably positioned perforations. Thus, when one of such perforations is brought into register with one of the pins 213, Figure 10, the corresponding circuit will be closed at the end of the run of the carriage and when the proper contacts on the carriage engage corresponding contacts at either end of the machine, the lock change controlling mechanism will operate in the manner hereinafter described. For this purpose, I have including in the knitting machine embodying my invention suitable jack engaging members and means for controlling the longitudinal and vertical needle operating movement of the jacks. Referring to Figure 17, which shows the bottom surface of the cam carriage, cam surfaces 401 and 402 are arranged to ride over portions of the jacks, normally depressing the same into needle engaging position, it being understood that double ended buttless needles are provided to move back and forth in the needle grooves of the needle

beds and that suitable jacks having needle hook engaging ends are also provided in the grooves to engage, disengage, and move the needles according to the requirements of the pattern of the knitted fabric. Adjacent to the cam surface 401 is a recessed portion 403, a similar recessed portion 404 lies adjacent to the cam surface 402, said recessed portions permitting the jacks to move up out of needle engaging position. It will be noted that the fixed cams lying adjacent to the rear needle bed of the machine will form a cam groove 405 while the fixed cams lying adjacent to the front needle bed will form a cam groove 406, said grooves cooperating in the well known way with the jack butts to move the jacks forward and back in their corresponding grooves in the needle beds. When the needles are positioned in one of the beds, they will normally be in contact only with the jacks belonging to that particular bed. However, where it is desired to interchange the needles from one bed to another for the purpose of changing the pattern, or the appearance of the knitted fabric, or for some other purpose, means may be provided to move the needles in one bed toward the center and into such a position that under some circumstances the jacks in the opposite bed will engage the free end of the needles to move the same immediately after the jacks in the other bed have been disengaged therefrom. This result may conveniently be controlled entirely from one side of the machine, preferably by means of a suitable cam co-operating with the jacks in the front bed. For this purpose, I have provided a vertically slideable or plunger cam 407 adapted to project, when operative, into the cam groove 406. A similarly shaped fixed cam 408 forms a part of the cam system co-operating with the rear bed of the machine and is equivalent to the cam 407 in every respect except that it is not removable or adjustable. Thus, at every links passage of the carriage or movement toward the left, the cam 408 thrusts the jacks and the needles forward into such position that the needles can be engaged by jacks in the front bed if said jacks are thrust forward sufficiently for the purpose. This is the function of the vertically slideable cam 407. When this cam is out of operation on links passage of the carriage, the jacks in the front bed do not engage the free end of the needles in the rear bed and therefore said needles are not drawn across into the front bed. However, when the cam 407 is moved into position in the cam slot 406, the jacks in the front bed are moved forward sufficiently to engage the free ends of the needles of the rear bed and said needles are withdrawn from said rear bed, but only when the carriage is moving in the direction indicated by the arrow. When moving in the opposite direction, the

same positioning of cam 407 will cause the needles in the front bed to be moved into the rear bed. The operations thus far referred to generally in connection with changes from links links to flat and vice versa are carried out in principle by the knitting machines in common use. However, according to my invention, I provide a novel and relatively simple and effective control over the movement of cam 407 so that changes in the position of said cam required by the pattern may be automatically and accurately brought about by electrical means.

Referring now to Figures 18 to 24 inclusive, the cam 407 may be supported on a link 438 pivotally mounted on a crank pin 409 projecting from the surface of a disc 410, said disc being attached to a rotating armature associated with magnet cores 411, 412 and 413, said armature being indicated at 414 (Figure 19). According to the present construction, the mechanism controlling cam 407 is capable of three positions illustrated at X, Y and Z in Figure 22. The X position is brought about when core 413 is energized, the Z position when core 411 is energized, and the Y position when the flow of current is induced in core 412. The X and Z positions produce what is called flat operation, while the Y position produces the links links operation or that positioning of the cam 407 which causes the needles to be shifted from one bed to the other. This mechanism is indicated diagrammatically in Figure 7 at M, in accordance with which, the circuit 15 controls core 411 but energizes said core only when the contact is closed at the left hand end of the machine or in the H group of fixed contacts. A similar circuit 15 is closed to energize core 413 when the carriage reaches the right end of its run, assuming in each case that a corresponding perforation in chart 218 permits the complete closing of the circuit through the control chart in the manner hereinabove explained generally. The core 412 may be energized at either end of the course of the carriage and is connected with the circuit 16 which includes not only the conductors indicated diagrammatically in the drawing (Figure 7) but also a plurality of spring contacts 415, 416, and 417. A metallic insulated contact plate 418 is mounted to rotate on the same center as the disc 410 but at the opposite end of the rod or member supporting both said disc and the armature 414. The contact plate 418 has a sector shaped recess arranged to expose a surface 420 of fibrous or other insulating material underlying the plate and therefore in the path of the contacts 415 and 417, depending upon which of the coils is energized. Thus, when the parts are in the position shown in Figure 19 or in the links links position, a perforation occurring in

the control chart along the line of circuit 15 will close said circuit and thus energize one of the magnets 411 or 413. Assuming that the core 411 is energized and that the 5 parts now assume the position Z of Figure 22, it will be clear that core 412 cannot be energized when the carriage is at the right hand extremity of its course because the contact 415 will be resting upon the exposed 10 surface 430 of the fibre insulating material adjacent to the contact plate 418, even though a perforation occurs in the line of the circuit 16. In order, therefore, to move the cam 407 back to links links position, it 15 will be necessary to have a perforation in the circuit 16 occurring at such a place on the control chart that said circuit will be completed at the left hand extremity of the course of the carriage. This arrangement 20 is intended to eliminate the possibility of erroneous or untimely operation of the cam 407.

By reason of the character of the operations set in motion by the movement of 25 cam 407, it has been found desirable to interpose safety devices in such a manner that, unless a proper predetermined movement of cam 407 takes place, further operation of the machine will be prevented. In other 30 words, if cam 407 should fail for some reason to perform its function according to proper knitting practice, it is likely that serious injury might result to the machine if the succeeding operation were permitted to 35 be initiated. Even if no injury came to the machine, it is possible that there would be an error in the knitted fabric. One of such safety devices is associated with the disc 410. Referring to Figures 18 and 21, this 40 disc is shown with a plurality of peripheral notches or depressions 419, one notch being provided for each position of the contact plate 418, as indicated in Figure 22. A lever 420 pivoted at 421 has a roller 422 mounted at its free end and positioned to engage the peripheral surface of the disc 410, said roller being retained in yielding engagement with said surface by means of a spring 423. The lever 420 also carries adjacent to its free end a contact 424 which is movable toward and away from a fixed contact 425. In operation, when the disc 410 is rotated by reason of the energizing of 45 one of the cores 411, 412 or 413, the roller 422 rides up on the cylindrical surface of the disc and closes the contacts 424-425. However, as soon as the change is completed and the roller 422 comes to rest in contact with one of the notches or recesses 419, the 50 contact 424-425 is again broken. These contacts may be included in one of the circuits indicated diagrammatically in Figure 8, and any one of which, when closed, will break the power circuit through operation 55 of the relay G. Thus, if for some reason 60

the change of position of cam 407 from position Y to position X should not be entirely completed, the roller 422 would still be riding on the cylindrical peripheral surface of the disc 410 and the contact 424-425 would be closed, thus energizing the magnet of relay G, and if all other settings and adjustments were correct, the machine would stop and the safety signals would indicate an incorrect functioning in connection with 70 cam 407. However, in normal operation, the change takes place at either end of the machine and substantially simultaneously with the periodic stopping and reversing of the motor so that the closing of the contacts 75 424, 425 does not interfere with continuous and effective operation.

I have previously referred to the jacquard or the mechanism for grouping, according to a predetermined plan, the jacks in the rear needle bed in such a manner that some or all of said jacks may be thrown into operative needle engaging position in their respective grooves. Before a rearrangement takes place, however, it is necessary to move 80 the disengaged jacks in the rear needle bed from working position toward the rear of the bed. This operation is accomplished by means of mechanism which I have identified generally in Figure 7 at N and which may 85 conveniently be referred to as the jack switch mechanism, the mechanical features of which are more clearly shown in Figures 13 to 17 inclusive. Referring to Figure 17, the actual jack engaging portion of 90 the mechanism includes a switch or cam 501, interposed in the cam groove 405 in the path of the jack butts, said switch being secured to the lower end of a rod 502 (Figure 14), the upper end of which carries an armature 95 503 (Figure 15) positioned to cooperate with the core of a magnet 504. A yielding latch 505 engages flat surfaces of the armature 503 to retain said armature in on and off positions, respectively. Referring now to Figure 7, the magnet 504 is energized through the circuit having the contacts 11, one of which is mounted on the reciprocating carriage of the machine, and the other of which is included in the group of contacts J, or those positioned at the right hand end of the machine. Thus, the energizing of magnet 504 can take place only at one end of the machine and when a perforation occurs in the control chart at the proper place to effect this result. Furthermore, the energizing of magnet 504 cannot take place unless the cam 407 is in position to effect 110 links links operation of the machine. In a full automatic machine, this result is accomplished by interposing a contact 506 (Figures 7 and 21) in the circuit 11, said contact being arranged in the path of the crank pin 409 on disc 410, and in engagement with 115 said crank pin or a contiguous part only 120 125 130

when cam 407 is in the Y, or links links position. In all other positions, these contacts are out of engagement and the jack switch circuit is open. Obviously, a similarly effective movement of the cam 407 may be made by mechanical means or by hand.

From the foregoing description of my improved knitting machine lock change mechanism and the features associated therewith, 10 it will be apparent that I have devised an effective means for changing the needles from one bed to the other. At the same 15 time, I have provided safety devices for protecting the machine against damage from untimely operation of the parts. Furthermore, I have provided reliable and convenient means for controlling operation of the jack switch so that it will operate only when the plunger cam is operating. If the plunger cam were not down or in links links 20 position, no useful result would follow from moving the switch 501 into operative position because the needles would not be properly positioned to respond to the desired 25 change.

I claim as my invention:

1. In a knitting machine, the combination of a cam carriage, front and rear cam grooves formed by cams on said carriage, a 30 cam supported on the carriage and movable into and out of effective jack operating position in one of said grooves, and electrically actuated means for moving said cam including a rotatable armature operatively positioned with respect to a plurality of magnets, a link connection between said cam and the armature, and means for energizing the magnets to rotate the armature into different cam positioning positions.
2. In a knitting machine, the combination of a cam carriage, front and rear cam grooves formed by cams on said carriage, a 35 cam supported on the carriage and movable into and out of effective jack operating position in one of said grooves, and electrically actuated means for moving said cam including a rotatable armature operatively positioned with respect to a plurality of magnets, a link connection between said cam and the armature, and means for selectively 40 energizing the magnets including a circuit having periodically engaging contacts and contacts adapted to engage coincident with predetermined engagements of the periodically 45 engaging contacts.
3. In a knitting machine, the combination of opposed needle beds, a cam carriage mounted to reciprocate in jack operating 50 relation to said needle beds, a jack actuating plunger cam on said carriage and electrically operated means for moving said cam into and out of operative position at predetermined intervals, comprising a plurality 55 of circuits having magnets, cam carrying means operatively arranged with respect to

said magnets, and means for closing said circuits to selectively energize the magnets.

4. In a knitting machine the combination of a reciprocating carriage, a driving motor therefor, a switch in the motor circuit, a jack actuating cam on the carriage, means for moving said cam into or out of jack actuating position at the end of a run of the carriage, and means cooperating with said cam moving means to open said motor 75 circuit switch when the cam is being moved from one position to another.

5. In a knitting machine the combination of a reciprocating carriage, a driving motor therefor, a switch in a motor circuit, a jack 80 actuating cam on the carriage, means for moving said cam into or out of jack actuating position at the end of a run of the carriage, and means cooperating with said cam moving means to open said motor circuit 85 switch when the cam is being moved from one position to another, said means comprising a relay positioned to actuate the motor circuit switch, a fixed terminal in the relay circuit, and a movable terminal in said circuit 90 actuated by the cam moving means.

6. In a knitting machine the combination of a reciprocating cam carriage, a jack actuating cam slidably mounted thereon, electrically operated means for actuating the 95 cam including separate circuits, a terminal at the end of each run of the carriage, terminals on the carriage positioned to engage said end terminals, and circuit making and breaking means adapted to close the respective circuits at predetermined intervals to actuate the cam at the end of a run of the carriage.

7. Cam control mechanism for knitting machines having a reciprocating cam carriage, comprising a cam actuating member on said carriage, means for operatively moving said member including an armature, a magnetic circuit, and means for closing said circuit at the end of a run of the carriage 105 to effectively move the armature.

8. Cam control mechanism for knitting machines having a reciprocating cam carriage comprising a cam actuating member on said carriage rotatable to cam elevating and cam depressing positions, and means for operatively moving said member including an armature operatively connected and rotatable therewith, a magnetic circuit, and means for closing said circuit at the end of 110 a run of the carriage to rotate the armature.

9. Cam control mechanism for knitting machines having a reciprocating cam carriage, comprising a cam actuating member on said carriage, means for operatively moving said member including an armature, a magnetic circuit having periodically closing contacts, make and break means normally open and means for closing said make and break means to coincide with any predetermined 120

mined periodic closing of said contacts to move the armature.

10. Cam control mechanism for knitting machines having a reciprocating cam carriage, comprising a cam actuating member on said carriage, means for operatively moving said member including an armature, a magnetic circuit having contacts arranged to close at the end of a run of the carriage, make and break means normally open and

means operative during a run of the carriage for closing said make and break means whereby the closing of the circuit may be completed by closing of the contacts at the end of the run of the carriage. 15

In testimony whereof, I have signed my name to this specification this 13 day of July 1921.

WILLIAM FELS.
